[57] CLAIM

The ornamental design for a housing for a mail handling machine, as shown and described.

DESCRIPTION

FIG. 1 is a perspective view of a housing for a mail handling machine showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a perspective view of a second embodiment of the housing for a mail handling machine shown in FIG. 1.

FIG. 1

FIG. 2

FIG. 3

FIG. 4

FIG. 5

FIG. 6

FIG. 7
